UNITED STATES PATENT OFFICE.

HENRY R. CORKHILL, SR., OF ROCHESTER, NEW YORK, ASSIGNOR TO
ADOLPH SORGE, JR., OF SAME PLACE.

BUTTON-FLY-MARKING MACHINE.

SPECIFICATION forming part of Letters Patent No. 380,994, dated April 10, 1888.

Application filed May 13, 1887. Serial No. 235,039. (No model.)

To all whom it may concern:

Be it known that I, HENRY R. CORKHILL, Sr., a citizen of the United States, residing at Rochester, in the county of Monroe and State 5 of New York, have invented certain Improvements in Button and Button-Hole Marking Machines for Boots and Shoes, of which the following is a specification, reference being had to the accompanying drawings.

10 My invention relates to improvements in marking devices for button and button-hole marking machines for boots and shoes by which the operation of marking the correct locations of the buttons and button-holes on the shoe- 15 uppers is performed with increased facility and speed.

My invention consists in improvements on the marking devices described in the application of Hatfield and Sorge, No. 235,559, filed 20 April 20, 1887.

My improvements are fully described and illustrated in the following specification and accompanying drawings, and the novel features thereof specified in the claims annexed 25 to the said specification.

In the accompanying drawings, Figure 1 is a plan view of a button and button-hole marking machine, the upper platen being raised at an angle with the base. Fig. 2 is a plan view 30 of a marking device with my improved gages, showing the lateral adjustment of the gages for various widths of scallops by the full and dotted lines. Fig. 3 is a plan view of my improved marking device, showing 35 the longitudinal adjustment of the gages. Fig. 4 is a side elevation of a marking device, the shoe-upper being indicated by dotted lines to show its position when being marked. Fig. 5 is a vertical section on the 40 line $\alpha\alpha$, Fig. 1, showing an upper in position in the machine. Fig. 6 is a side elevation, and Fig. 7 a plan view, of a modified construction of my improved adjustable gages. Figs. 8 and 9 are a side elevation and plan view of another modification. Fig. 10 is a central vertical section on the line yy , Fig. 11. Fig. 11 is a plan view of another modification of my improved marking device.

45 A A represent the lower platen or base of 50 a button and button-hole marking machine.

D represents the lower clamp, which holds the fly N and lower quarter, L, firmly in position.

B B represent the upper swinging platen, and E the upper clamp, which holds the quarter M securely by means of the latch α . The upper clamp, E, is pivoted to the base by the arms $b b$, so that it can swing upward independently of the upper platen, B.

R represents the rod of the marking device, 60 which may have a handle attached to hold it with. The boss or standard T is firmly attached to this rod and carries the lower spring-plate or die, S, on which is a raised point fitting into a countersink in the bottom of the 65 boss T. On the upper surface of boss T another raised point is formed. The curved spring c holds the die S away from the boss T until a blow or pressure forces them together.

Two wires, U U', Figs. 2, 3, and 4, are securely attached to a yoke, Z, which slides on rod R, and which may be secured in any desired position by means of a set-screw or equivalent device. The two wires U U' are fastened closely together at the ends, where 75 they are secured to the yoke Z, but are spread apart at their other end while being bent down also until the points touch the plate S. A clamp or yoke, W, slides on the rod R, through holes in which the wires U U' pass. These 80 holes are not as far apart as the bent points of wires U U'. This clamp can also be securely fixed at any desired position on the rod R by means of the set-screw shown. The ends of the wires U U' act as gage-pins by 85 being drawn into the notches between the scallops on the fly, as shown in Fig. 1.

If a certain width of scallop is to be marked, the clamp W is moved until the spread of the ends of the wires U U' is equal to that width, 90 and the set-screw is then used to hold the clamp in the desired position, as shown in Fig. 2. In order to vary the distance back from the edge of the scallop at which the mark is to be made, the yoke Z is moved until the desired position 95 is obtained, as shown in Fig. 3, and then the set-screw is forced in and the clamp W is adjusted. Instead of two wires, U U', a single wire may be sharply bent at Z and its two ends formed as though each were a separate wire. 100

Fig. 6 and 7 represent a modification of my improved adjustable gages. In this case a rod, V, slides through a hole provided in the boss T, and a set-screw in the boss securely holds this rod in any desired position. In this case the wire or wires U U' are secured to the end of the rod V, and the clamp W, which is constructed as already described, can be moved on the rod V. Still another modification of my improved gages is shown in Figs. 8 and 9, where the rod V passes through the boss T and can be secured by a set-screw, as shown. However, in this case the clamp is dispensed with by which the width of the gages is adjusted to that of the scallops, and rigidly-attached wires U U' of various spread, each on a separate rod, V, are employed. When it is desired to mark uppers of a given width of scallop, the rod V, carrying the wires U U' of the desired spread, is inserted and adjusted to the desired position. One rod, V, only may also be employed in this last case, and then the wires U U' are each time bent to the required width.

In the accompanying drawings the clamp W and yoke Z are shown as being held in position by set-screws; but they may also be made to fit snugly on the rods, and the friction caused by such snug fitting will hold them in whatever position they are placed.

In the style of marking device described in the application before mentioned the lower die is connected to the boss by the spring e, which is compressed at each blow of the upper platen. These continued blows or compressions gradually weaken the spring. In order to obviate this difficulty, I have invented the marking device shown in Figs. 10 and 11. The rod R is attached to a rigid carrier, O, to which the die S is firmly secured, as shown. A hole is drilled

through this carrier vertically, and a punch, 40 T, slides freely in this hole, and is provided at the top with a raised point and at the bottom with a countersink fitting over a raised point on the die S. A small spring, P, is attached to the punch and to the carrier, so that it continually tends to raise the punch, a slot 45 in the carrier permitting this spring to work freely.

The application of this improved marking device when marking uppers is the same as before described, but all bending strain upon the die S or spring e is avoided. The spring P can be replaced easily and cheaply.

I do not claim the marking-machine or any part of it, as this is the invention of Charles 55 B. Hatfield and Adolph Sorge, Jr.

I claim—

1. In a button and button-hole marking machine, the combination of a marking device, as R S T, and the adjustable gages U U', substantially as described.

2. In a button and button-hole marking machine, the combination of a marking device, as R S T, adjustable gages U U', and sliding clamp W, substantially as described.

3. In a button and button-hole marking machine, the combination of a marking device, as R S T, adjustable gages U U', sliding clamp W, and sliding yoke Z, substantially as described.

4. In a button and button-hole marking machine, the combination of a marking device, as R S T, adjustable gages U U', and sliding rod V, substantially as described.

HENRY R. CORKHILL, SR.
